SUCTION CLEANING AND SWEEPING
MACHINEWilliam Johnston Frame, Putney, London, and
John James Hambridge, Wandsworth Common,
London, EnglandApplication August 19, 1936, Serial No. 96,866
In Great Britain August 23, 1935

8 Claims. (Cl. 15—9)

This invention relates to suction cleaning and sweeping machines of the kind wherein a rotary brush or brushes is or are disposed within a suction nozzle adapted to be traversed over a floor or other surface to be cleaned.

The object of the present invention is to provide an improved construction and arrangement of suction cleaning and sweeping machine designed to enable the drive to the sweeper member or members to be disconnected and also by the same operation if desired the floor nozzle suction passage to be closed and the suction diverted to another passage or passages to which a connection or connections can be made for cleaning articles and surfaces.

According to the invention a suction cleaning and sweeping machine is provided wherein a rotary brush or brushes in the suction nozzle is or are driven by a belt from a shaft mounted coaxially with the fan shaft, the two shafts being capable of connection by means of a clutch device.

The invention also consists in a suction cleaning and sweeping machine including an electric motor and a fan mounted on a horizontal axis, a shaft constituting an extension of the fan shaft, a belt drive between said extensions and a brush or brushes in the suction nozzle, clutch members adapted to couple the fan shaft and extension and manually operated means for connecting and disconnecting said shafts.

The invention further consists in a suction cleaning and sweeping machine wherein a valve controls communication from a suction producer to a floor nozzle and is so arranged that when the valve is moved to the closed floor nozzle position such operation puts the drive to the rotary brush member out of action and at the same time one or more secondary air passages are put in communication with the suction producer for the purpose of enabling other surfaces or articles to be cleaned by suction.

The invention still further consists in a suction cleaning and sweeping machine including a floor nozzle or nozzles, a rotary brush or brushes disposed in one nozzle, a secondary air passage or passages and a combined valve and clutch device capable of partial rotation by hand to a position in which the brush is driven and a suction producer is placed in communication with said floor nozzle or to an alternative position in which the brush is disconnected from its driving means and the suction producer placed in communication with the secondary air passage or passages.

Reference will now be made to the accompanying drawings which illustrate by way of exam-

ple a machine constructed according to the invention and in which:—

Fig. 1 is a longitudinal sectional elevation,

Fig. 2 is a front elevation partly in section,

Fig. 3 is a rear elevation,

Fig. 4 is a plan,

Fig. 5 is a fragmentary sectional elevation showing the position of the parts when the drive to the brushes is disconnected,

Fig. 6 is a perspective view of the valve element,

Fig. 7 is a diagram of the electrical circuit arrangements, and

Fig. 8 is a longitudinal sectional elevation of a modified construction.

In the construction illustrated the improved suction cleaning and sweeping machine comprises a main casing 1 which contains an electric driving motor 2 the spindle 3 of which extends into a fan chamber 4 and carries a suction creating fan 5. The casing 1 has also a forward extension 6 embodying the drive hereinafter described to rotary brushes 7 removably mounted within a floor suction nozzle 8 constituting a downward extension of the aforesaid forward extension 6 of the main casing.

The forward end of the power operated shaft 3 has mounted thereon a friction clutch element 9 which is slidable over the end of the shaft and has a pin and slot connection 10 therewith, the clutch member being urged by a spring 11 into engagement with a co-operating friction clutch member 12 which is preferably formed of cork and is mounted on the inner end of a shaft 13 constituting a co-axial extension of the shaft 3 and carrying at its outer end a pulley 14 from which the drive is transmitted by a belt 15 to a pulley 16 formed at the centre of the brush spindle 17.

The extension shaft 13 is carried in a combined clutch and valve unit capable of adjustment by means of a handle 18 which projects through the top of the casing extension 6. In the position shown in Fig. 1 the suction fan chamber 4 is in communication with the floor nozzle 8 through a port 19 formed in a cylindrical valve member 20 which port communicates with a suction passage 21 formed in the base of the forward extension 6 of the main casing. Above the passage 21 is formed a cylindrical socket 22 in which the valve member 20 is rotatably mounted. Within the valve member is fixed a tubular element 23 which encloses the co-operating clutch elements 9 and 12 and has fixed within it a sleeve 24 carrying bearings 25 for the extension shaft 13.

13. The handle 18 is fixed into the valve member 20 by means of a screw threaded shank and a nut 26 and the handle projects through a relatively wide slot 27 in the casing extension 6 which 5 slot is covered by a plate 28 having a narrow slot 29 inclined to the horizontal axis of the machine (see Fig. 4). With this arrangement movement of the handle 18 from one end of the slot 28 to the other will impart a combined rotational 10 and axial movement to the valve member 20 and the parts mounted therein including the extension shaft 13. In this manner the clutch member 12 can be brought into and out of driven engagement with the clutch member 9 as required.

15. By employing a separate shaft 13 which carries the driving pulley 14 for the brush spindles certain advantages accrue, the first of which is that the cantilever pull of the belt 15 is not transferred to the bearings of the main power 20 shaft 3 and secondly, the friction clutch arrangement 9 and 12 may be arranged so that slip or disengagement can take place if the brushes should jam or if an overload occurs on the drive.

When the combined valve and clutch element 25 is partially rotated and axially moved to occupy the position shown in Fig. 5 the outer cylindrical portion of the valve member closes the passage 21 and the port 19 is brought into alignment with a port 30 at one side of the main casing 1, this 30 port leading to a short passage 31 to which a flexible hose or other connection can be attached for the purpose of cleaning surfaces or articles other than floors or floor areas which are inaccessible to the machine as a whole. Alternatively 35 the passage 31 may be arranged to communicate with a secondary floor nozzle brought into operation for cleaning only by suction when the brush is inoperative. In the position of the valve member shown in Fig. 5 the clutch members 9 and 12 are disengaged and the drive to the brush ceases. The ends of the brush spindle 17 are mounted in ball races 32, the housings of which are detachably carried in spring clips 33 fixed in the end walls 34 of the suction nozzle 8. 40 This nozzle is completed at its under side by means of a sheet metal trough 35 having an opening or openings 36 formed in its base and extending through substantially the width of the nozzle and this trough is adapted to be sprung 45 into position by causing a beading 37 along its rear edge to engage above the edge of a curved plate 38 fixed adjacent the lower edge of the casing extension 6 but capable of slight movement against the action of a spring 39 to allow 50 the trough 35 to be sprung into position.

The distance of the brushes 7 and the suction nozzle 8 from the floor surface may be adjusted by means of a rotary brush level control device 40 mounted on one side of the casing 1 and 55 operating a spindle connected through a crank and rod 41 to the forward end of a frame 42 pivoted at 43 to the casing 1 and carrying floor wheels 44. Raising or lowering of the connecting rod 41 will therefore adjust the position of the suction nozzle 8 and brushes 7.

60 The machine is provided with a propelling handle 45 which is pivoted to the sides of the casing at 46 and which has clamped to it a projecting arm 47 which is slotted at one end so that when it is desired to fix the handle relatively 65 to the casing for the purpose of floor polishing the end of the arm 47 is caused to engage around a screw 48 which enters the rear end of the casing 1. When not in use the arm 47 is moved 70 to the position shown in Fig. 3 in which it occu-

pies a position coincident with one arm of the handle 45.

The rear portion of the casing 1 constitutes the motor housing, the motor being resiliently mounted between a buffer 49 of india rubber at its rear end and an annular india rubber disc 50 5 against which bears a flange 51 at the forward end of the motor casing. The annular disc 50 is mounted in a metal disc 52 which is held in position between co-operating parts of the fan 10 chamber 4.

The upper portion of the machine is preferably 15 provided with an insulated housing 53 which serves to enclose certain electrical components of the machine. The forward end of this housing is formed as a hood 54 for a lamp 55 arranged to illuminate the floor area ahead of the machine. The rear portion of the housing 53 is formed as a socket 56 in which are disposed contact pins 57 to engage an adaptor 58 to which 20 are attached flexible electrical conductors communicating with a source of electric current supply. These contact pins are electrically connected to the motor 2, a switch 59, the lamp 55 and a lamp resistance 60, the connections between these components being illustrated in Fig. 7. The rear portion of the housing 53 slopes 25 downwardly so that the operating arm of the switch 59 does not project above the top of the housing and is thus protected against accidental 30 operation.

To prevent overheating of the interior of the housing 53 air for cooling is caused to circulate through it whilst the machine is in operation by 35 providing an opening 61 in the base of the housing communicating with the interior of the motor housing which is provided with an air inlet or inlets 62. Air vents 63 are also provided in the housing 53 whilst air passages 64 communicating with the interior of the housing extend to the eye 40 of the fan 5.

The delivery from the fan passes through an outlet 65 to which a filter bag is connected in the usual manner.

The rear portion of the main casing 1 is supported on a pair of wheels 66 mounted in a common bearing arranged to swivel about a pin 67. 45

In the alternative construction illustrated in Fig. 8 parts having similar functions to those illustrated in Figs. 1-7 are indicated by the same 50 reference numerals. In this construction the valve member 20 is omitted, the clutch members 17 and 18 being employed in a normal suction nozzle to connect or disconnect the drive to the rotary brushes 7. In this arrangement the operating handle or lever 18 instead of being fixed in the valve member is fixed in a sleeve 68 capable of rotational and axial adjustment and which carries the tubular member 23. The handle or lever 18 is movable in an inclined slot similar to 60 that shown at 29 in Fig. 4 for the purpose of effecting axial movement of the extension shaft 13 as before.

We claim:

1. A suction cleaning and sweeping machine 65 comprising a casing terminating in a suction nozzle and having a secondary suction inlet, rotary brush elements mounted in said nozzle, a suction fan mounted on a horizontal shaft in the casing, a valve member mounted in the casing coaxially with said shaft and operable to connect the suction nozzle or the secondary suction inlet to the suction portion of the fan, an extension shaft in the casing coaxial with said fan shaft, a driving connection between said extension shaft and said 70 75

brush elements, clutch elements mounted on the adjacent ends of the fan shaft and the extension shaft, and a hand operated sleeve carrying said extension shaft and connected to said valve member to operate therewith and movable axially to control said clutch elements in accordance with the operation of said valve member.

5 2. A suction cleaning and sweeping machine according to claim 1, wherein said sleeve extends over said clutch elements.

10 3. A suction cleaning and sweeping machine comprising a casing, a floor nozzle having a passage leading into said casing, the casing having a passage for a secondary nozzle at a side of and leading into said casing, a suction fan in said casing, a rotary brush in said floor nozzle, a rotary valve in said casing rotatable to place either of said passages in communication with said fan, a horizontal shaft carrying said fan, a horizontal extension shaft carried by said rotary valve, a driving connection between said extension shaft and said brush, clutch elements mounted respectively on said shafts and capable of connecting said shafts and controlled by axial movement of said extension shaft, and means for imparting partial rotary and axial movements to said valve and extension shaft.

15 4. A suction cleaning and sweeping machine comprising a casing having a suction floor nozzle connected thereto and also having a secondary suction inlet, a rotary brush mounted in said nozzle, a suction fan in the casing having a shaft for driving it, a valve member mounted in the casing and operative to connect said floor nozzle or said secondary suction inlet to the suction portion of the fan, a sleeve mounted in the casing beyond the fan shaft and movable axially thereof when said valve member is operated, an extension shaft mounted coaxially in the sleeve in alinement with the fan shaft and movable axially with said sleeve, driving means for connecting the extension shaft to the brush, and driving clutch members on the adjacent ends of the fan shaft and the extension shaft and engageable and disengageable by axial movements of said sleeve.

20 5. A suction cleaning and sweeping machine comprising a casing having a suction floor nozzle connected thereto and also having a secondary suction inlet, a rotary brush mounted in said nozzle, a suction fan having a supporting and driving shaft mounted in the casing, a valve member extending into the casing coaxially of the fan shaft, said valve member being rotatable to control the connection of the floor nozzle and said secondary suction inlet to the suction portion of the fan and simultaneously movable axially toward and from the fan shaft, an ex-

25 tension shaft mounted in the valve member in alinement with the fan shaft and movable axially with said valve member, driving clutch members on the inner end of the extension shaft and the adjacent end of the fan shaft controlled by axial movements of said valve member, and driving means connecting the outer end of the extension shaft to the brush.

30 6. A suction cleaning and sweeping machine comprising a casing, a suction fan mounted therein, a floor nozzle connected to the casing and having a port for connecting it to the suction portion of the fan, the casing having an inlet for the attachment of a suction conduit thereto and provided with a port for connecting it to the suction portion of the fan, a brush mounted in the floor nozzle, a valve mounted to rotate and move axially in the casing coaxially of the fan shaft and having a port movable into communication with the floor nozzle port or the inlet port by rotation of the valve and a driving clutch controlled by the axial movement of the valve for connecting the brush to the fan shaft when the port in the valve is in communication with the floor nozzle port and for disconnecting said brush from the fan shaft when the port in the valve is in communication with said inlet port.

35 7. A suction cleaning and sweeping machine comprising a casing, a suction fan mounted therein, a floor nozzle connected to the casing and having a port for connecting it to the suction portion of the fan, the casing having an inlet for the attachment of a suction conduit thereto and provided with a port for connecting it to the suction portion of the fan, a brush mounted in the floor nozzle, a valve mounted to rotate and move axially in the casing coaxially of the fan shaft and having a port movable into communication with the floor nozzle port or the inlet port by rotation of the valve, an extension shaft mounted coaxially in said valve and movable axially therewith, a driving clutch for connecting one end of the extension shaft to the fan shaft when the valve is rotated to bring the port therein into communication with the floor nozzle port, and a driving belt located exteriorly of said valve and connecting the other end of the extension shaft to the brush in the floor

40 45 8. A suction cleaning and sweeping machine according to claim 6, wherein said valve is rotated and moved axially in the casing by an arm connected to the valve and operating in a slot in the casing which is inclined to the axis of the valve.

50 WILLIAM JOHNSTON FRAME.
JOHN JAMES HAMBIDGE.
